FLOODLIGHT

Myron F. Pettengill, Hendersonville, N.C., assignor to
General Electric Company, a corporation of New York

Filed Aug. 21, 1963, Ser. No. 76,306

Term of patent 14 years

(Cl. D48—20)

Fig. 1.

Fig. 3.

Fig. 2.

Fig. 5.

Fig. 4.

FIG. 1 is a perspective view of a floodlight showing my new design;

FIG. 2 is a front elevational view;

FIG. 3 is a top plan view;

FIG. 4 is a side elevational view; and

FIG. 5 is a rear elevational view thereof.

The unshown end is substantially the same in appearance as the end shown.

This application is a continuation in part of application Serial No. D. 71,426, filed Aug. 23, 1962 and now abandoned.

I claim:

The ornamental design for a floodlight, as shown and described.
